UNITED STATES PATENT OFFICE.

EMIL A. NELSON, OF DETROIT, MICHIGAN, ASSIGNOR TO WILLIAM J. NEWTON
AND CHARLES J. WOODALL, OF DETROIT, MICHIGAN.

STARTING MEANS FOR EXPLOSION-MOTORS.

No. 848,679.

Specification of Letters Patent.

Patented April 2, 1907.

Application filed January 24, 1906. Serial No. 297,625.

To all whom it may concern:

Be it known that I, EMIL A. NELSON, a citizen of the United States, residing at Detroit, in the county of Wayne and State of Michigan, have invented certain new and useful Improvements in Starting Means for Explosion-Motors, of which the following is a specification.

My invention relates to explosive-motors and to the starting appliances therefor, and consists in means whereby the starting-shaft can be rotated from a crank without the latter being turned by the rotation in either direction of said shaft, as fully set forth hereinafter and as illustrated in the accompanying drawings, in which—

Figure 1 is an elevation in part section of my improved starting device; Fig. 2, a plan; Figs. 3 and 4, elevations showing modifications; Fig. 5, a plan of Fig. 4.

The engine B, of any suitable character, is provided with a shaft E, geared in any way to be driven by the engine or the rotation of which will serve to start the engine, and upon this shaft is a worm-wheel 70, to which is adapted a worm 71, which may be turned by a handle 74 to rotate the worm-wheel and which may also be moved horizontally into and out of engagement with the worm-wheel.

As shown in Figs. 1 and 2, the worm 71 is connected to a shaft 72 tangential to the worm-wheel 70 and sliding in a bearing 73 of the frame and provided at the outer end with the handle. These parts are so arranged and proportioned that by sliding the handle-shaft 72 the worm may be brought to either of the positions shown at 1, 2, and 3 in the drawings. A spring 75 is suitably arranged and connected to tend to carry the worm to the position No. 1, but will yield to allow it to move to either of the other positions, exerting sufficient stress when the worm-wheel is in its central position to maintain it in gear with the worm-wheel during the rotation of the shafts in starting. When the shaft E begins to rotate at a greater speed than is imparted from the shaft 72, as the engine starts in action the worm can be thrown back to the position No. 1. The spring, however, is capable of being further compressed, so that if when turning the worm-wheel by the action of the shaft 72 there is a back action of the worm-wheel this movement of the latter will carry the worm to the position 3.

It will be seen by the arrangement of parts 55 set forth that while the rotation of the shaft 72 may be the means of rotating the shaft E the rotation of the latter has no tendency to rotate the shaft 72, but simply shifts the worm and shaft to carry the worm to one side or the other in a line tangential to the worm-wheel, and thus the accidents which result from the rotating action of the engine upon the handle-shaft are avoided. It will of course be evident that the spring 75 may be connected to secure the desired action in any suitable manner; but, as shown, the shaft 72 is hollow and can slide inward over a rod 76, fixed to a bracket 77, the spring 75 within the hollow shaft bearing against the end of 70 the said rod and against the outer end of the shaft.

In the construction shown in Fig. 3 the crank-shaft slides, the worm-wheel turning with and sliding on the shaft and being maintained in its position No. 2 by a spring 90, which is of such strength as not to yield when turning the worm-wheel after carrying it to position No. 2 to start the engine by pushing in the shaft; but when the motor starts in action the shaft and worm will be carried to position No. 1 and retained by a spring 91. The spring 90 will yield in case of back firing the worm-wheel is reversed. In the construction shown in Figs. 4 and 5 also the crank-shaft turns and the worm turns with and slides thereon. In this case a pair of springs 93 93 act to straighten toggles 96 96, connected to the worm and to a collar 94 on the shaft, and hold them with the joints a little 90 above the dead-center. The shaft is pushed in to bring the worm to the position No. 2 for turning the shaft E by hand. When the shaft, E begins to rotate by the action of the engine, the worm, with its shaft, is carried 95 to the left, a spring 95 tending to maintain them in this position. In case of back firing, the toggles will be bent against the stress of the springs, the worm being carried to the position No. 3.

Without limiting myself to the precise construction and arrangement shown,

I claim—

1. The combination with the shaft of a motor, of a worm-wheel, worm, and actuating-handle for starting the shaft, the worm movable tangentially in respect to the wheel to be thrown tangentially out of engagement

therewith on the rotation of the wheel faster than or in a different direction from the worm.

2. The combination with the shaft of a motor, of a worm-wheel thereon, a starting-shaft provided with a handle and carrying a worm, and a spring-support for the worm constructed to yield to permit the worm to be carried on the shaft by the wheel.

3. The combination with a shaft of a motor, of a worm-wheel, a worm, and means for turning the same to rotate the wheel, the worm mounted to slide to different positions out of engagement with the wheel under the action of the latter.

15. 4. The combination with the shaft of a motor, of a worm-wheel, a hand-shaft, a worm engaging said wheel and turning with said hand-shaft, means whereby the worm may be carried tangentially to, beneath, and 20 beyond said wheel, and a spring tending to hold the worm out of engagement with the wheel.

5. The combination with the shaft of a motor, of a worm-wheel, a hand-shaft, a 25 worm engaging said wheel and carried by said hand-shaft, means whereby the worm

may be carried tangentially to, beneath, and beyond said wheel, and means whereby the worm is permitted to slide tangentially in respect to the wheel when the wheel turns 30 faster than or in a different direction from the shaft.

6. The combination with the shaft of a motor, of a worm-wheel thereon, a starting-shaft provided with a handle and carrying a 35 worm, and a spring connected to be compressed as the worm is carried to a position engaging the wheel and capable of yielding to permit the worm to be carried by the wheel.

7. The combination with the shaft of a 40 motor carrying a worm-wheel, of a hollow starting-shaft carrying a worm and handle and mounted to slide longitudinally, and a spring arranged to carry the hand-shaft to a position with the worm at one side of the 45 wheel.

In testimony whereof I affix my signature in presence of two witnesses.
